UNITED STATES PATENT OFFICE.

GEORG MAX SCHÜLLER, OF KUNNERSDORF-UPON-THE-EIGEN, GERMANY.

METHOD OF MIXING LOOSE FIBROUS MATERIAL.

1,134,163.

Specification of Letters Patent.

Patented Apr. 6, 1915.

Application filed November 12, 1913. Serial No. 800,452.

To all whom it may concern:

Be it known that I, GEORG MAX SCHÜLLER, a subject of the King of Saxony, residing at Kunnersdorf-upon-the-Eigen, Saxony, in the 5 German Empire, have invented new and useful Improvements in the Method of Mixing Loose Fibrous Material, of which the following is a specification.

Loose raw fibrous material, like cotton, 10 generally comes into the market or the mills in bales of various forms, styles of packing, and size. It is essential that the contents of a bale should not be used alone but should be mixed with the contents of other bales in 15 order that the advantages and disadvantages of the contents of the several bales may be compensated.

All methods of mixing at present known 20 are too difficult for practice or the number of the bales that can be mixed is too limited or a special form of the bale is requisite for the method. For this reason none of the known methods have had any noteworthy 25 practical application so that there is still a need for a process certain in operation and requiring simple construction and little power (the new machine consumes only one horse-power) accompanied by a large output; the process should also not require supervision.

According to the process constituting the 30 subject matter of the present invention, complete mixing of the fibers is obtained by laying thin vertical layers in the horizontal 35 plane spirally side by side, each layer being displaced by a fraction of the periphery, for example one quarter (I, II, III, IV), and each spiral path beginning at the periphery of the horizontal plane and terminating toward its center.

The process may be applied by a machine 40 such as that which will now be described with reference to the accompanying drawings, in which—

Figure 1 is an elevation and Fig. 2 a plan.

A horizontal bridge 2 is adapted to turn 45 on a stationary circular rail 1 about the vertical axis M A thereof. Rail 1 has a diameter of 7 meters and is supported at a height of 4 meters above the floor. It may be constructed to move along rails supported by the walls of the room in order that it may be possible to lay several heaps side by side by means of one machine. On the bridge 2 runs a carriage 3 within which are

journalized two driven rollers over which extends an endless band 4. Co-axially with the circular rail is fixed a funnel 5, the lower diameter of which is about one-fifth smaller than the width of the band 4; this funnel is for the purpose of guiding on to the band 4 the fibrous material which is delivered to it by means of the conveyer band 6. A winding mechanism 7 draws the carriage 3 at uniform acceleration from *a* to *b*, 60 at the same time raising the weight 8; when the carriage arrives at point *b* the winding mechanism is thrown out of gear so that the weight 8 immediately returns the carriage to its starting point *a* whereupon the winding mechanism 7 is again thrown into gear for repeating the operation. The acceleration increases in the same proportion as the surface to be covered by the fibrous material diminishes. This results in the 70 production of a uniform depth of the material laid along the entire length of each spiral path.

The operation is as follows:—The breaker 80 lays the released fibrous material on the conveyer band 6 which feeds the material through the funnel 5 on to the belt 4 whence it falls over the front roller of the carriage 3. Meanwhile the bridge 2 moves once over I, II, III, IV and the winding mechanism 85 7 draws the carriage 3 with uniform acceleration from *a* to *b* so that the fibrous material as it falls from the carriage is laid in a spiral path. When the first spiral has been laid 90 (after one revolution of the bridge and one travel of the carriage from *a* to *b*) the winding mechanism is thrown out of gear, the carriage is drawn back and begins at II to lay a fresh spiral. This work proceeds 95 automatically until the depth available, *H*, has been filled. The extent to which the contents of a single bale may be distributed by this method shall now be made clear by way of an example: A bale of cotton, for instance, weighs about 220 kilograms and the cotton occupies a space of about 2 cubic meters after it has been passed through the breaker. Supposing, the machine for carrying out this method is constructed to cover a 100 layer surface of a diameter of 7 meters; the winding mechanism shall be adjusted to describe four spiral paths in each layer (a machine can lay 6, 8, 10, or any desired number of spirals if the winding mechanism is 105 correspondingly constructed with change wheels), and the speed of the carriage is 110

proportioned so that one layer is produced with the contents of one bale. The depth of a single layer would then amount to about 0.05 meters, that means that approximately 5 80 bales would go into the available space of four meters depth. From the heap thus laid the fibrous material is taken in form of cylindrical segments cut out of the heap to the number of twelve, for example. From this 10 it may be seen that while the contents of one bale is spread out into a horizontal layer, it is already thoroughly mixed by being composed of a number of spiral paths. Since each layer is divided into twelve sections, a 15 twelfth part of each bale constitutes the eightieth part of each cylindrical segment taken from the laid heap.

Copies of this patent may be obtained for five cents each, by addressing the "Commissioner of Patents, Washington, D. C."

I claim:

A method of mixing loose fibrous material, consisting in spreading the fibrous material over a relatively large horizontal plane in thin superposed layers and causing the fiber to follow with accelerating speed, 20 spiral paths in producing each horizontal layer, each of which spiral paths beginning 25 at the periphery of each horizontal layer, at a point advanced from the peripheral starting point of the preceding spiral, and terminating toward the center of the horizontal layer, substantially as set forth.

GEORG MAX SCHÜLLER.
